UNITED STATES PATENT OFFICE.

BENJAMIN ALFRED DOBSON, OF BOLTON, COUNTY OF LANCASTER, ENGLAND.

MACHINE FOR WINDING YARN.

SPECIFICATION forming part of Letters Patent No. 367,966, dated August 9, 1887.

Application filed October 23, 1886. Serial No. 216,995. (No model.) Patented in England January 13, 1885, No. 429.

To all whom it may concern:

Be it known that I, BENJAMIN ALFRED DOBSON, a subject of the Queen of Great Britain, residing at Bolton, in the county of Lancaster, England, have invented certain Improvements in Machinery for Winding Yarn, (for which I have obtained a patent in Great Britain, No. 429, bearing date January 13, 1885,) of which the following is a specification.

My invention relates to machines for winding yarn; and it consists, chiefly, in an improved combination and arrangement of parts, hereinafter fully described, and particularly 15 pointed out in the claims, my object being to stop the winding automatically when the yarn breaks or fails, to provide improved means for regulating the tension on the threads, and to give greater facilities for piecing up the broken 20 threads.

Reference is to be had to the accompanying drawings, forming a part of this specification, in which similar letters of reference indicate corresponding parts in both the figures.

25 Figure 1 is an elevation, partly in section, and Fig. 2 a plan, of part of a machine for winding yarn to which my improvements have been applied.

a is the driving-drum, mounted on the 30 shaft *a'*.

b is an intermediate roller supported in open bearings in the stationary bracket *c*, which is bolted to the rail *d*. To the other end of the bracket *c* is pivoted one end of the movable bracket *e*, which carries the bobbin *f*, and from 35 which is suspended the weighted wire *e'*.

The brake-block or wedge *g* is made with or attached to the rod or spindle *g'*, which passes through the bracket *c* and is supported by it 40 as well as by the brake-block *g*, which is fitted in a groove or slide, *c'*, in the bracket *c*. A spiral spring, *h*, is coiled upon the spindle *g'* and compressed between one side of the bracket *c* and the brake-block *g*. Secured to the front 45 end of the spindle *g'* by a screw, *i*, is the starting-handle *j*, which has a projection, *j'*, engaging with a projection or tail-piece, *k'*, on the oscillating needle-box *k*. The needle-box *k* is free to swing on pivots *k* in the brackets *l*, 50 which are secured to the front rail, *m*.

n are the needles, and *o* is the wing or wiper

shaft, revolving in suitable bearings in the brackets *l* below the needle-box.

The yarn passes from the cops or bobbins through guides *p* over the first long bar or 55 drag-wire, *r*, which is supported on an adjusting-screw, *r'*, in a slotted bracket, *s*, at each side of the machine. The other end of the bracket *s*, which is secured to the front rail, *m*, carries the second long bar or drag-wire, *t*. 60 The bars *r* and *t* both extend the full width of the machine, and the bar *t* carries a tension-wire, *u*, for each stop-motion. One such tension-wire *u* only is shown, the same swinging on the bar *t* by means of twists or loops in the 65 wire, and being provided with a prolongation, *u'*, connected by a wire, *v*, to the brake-block *g*, to which the wire is secured by a set-screw, *w*. The bar *r* may be raised or lowered by the adjusting-screws *r'*, and the position of the 70 tension-wires *u* may be adjusted by means of the wire *v* and the set-screw *w* so as to alter the relative positions of the three wires *r*, *t*, and *u* and regulate the amount of tension on the yarn, it being obvious that by slackening the 75 screw *w* and moving the wire *v* endwise the position of the wire *u* relatively to the wires *r* and *t* will be readily changed. The yarn passes from the cops or bobbins through the 80 guides *p*, over the bar *r*, under the tension-wire *u*, over the second bar, *t*, down through the eyes of the needles *n*, over guide-pulleys, (not shown,) and so to the bobbin *f*.

When a thread breaks its needle *n* falls and is struck by the revolving wing-shaft *o*, which 85 moves the oscillating needle-box *k* and withdraws its tail-piece *k'* from under the projection *j'*, thus unlatching the starting-handle *j*, releasing the spindle *g'*, and allowing the spring *h* to shoot the spindle and wedge *g* back, thereby raising the intermediate roller *b* out of contact with the driving-drum *a*, and so stopping the bobbin *f*. When the brake-block *g* slides, the wire *v*, moving with it, causes the tension-wire *u* to turn up into the position indicated by dotted lines, Fig. 1, thus bringing the three wires *r*, *t*, and *u* into line, or nearly so, and leaving the yarn slack, thereby facilitating the piecing up. When an end is lost the operative raises the bracket *e* and bobbin *f* sufficiently to allow the knee *e'* in the wire *e'* 90 to rest upon the bracket *c* and support the 95 100

bracket *e*, and thus leave the operative both hands free for piecing the ends of the broken thread. When the spindle *g'* is drawn back by means of the starting-handle *j* to restart the intermediate roller, *b*, the back of the wedge *g* comes against the knee *e'*, knocks the knee *e'* off the bracket *e* and restarts the bobbin.

In place of using the improved drag apparatus herein shown and described, the yarn may pass from the cops or bobbins over a drag-board directly to the detector-needles *n*, and thence to the bobbin *f*.

When the needle employed is formed with a knee, as shown in the drawings, the slot in which it is confined is cut at such an angle that with the aid of a plate, *n'*, adjusted in position by a screw-bolt, *n''*, and resting in contact with the needle, the needle, when suspended by the thread, will hang free from contact with the front and back of said slot.

Having stated the nature of my invention and described the manner of performing the same, I declare that what I claim, and desire to secure by Letters Patent of the United States, is—

1. In yarn-winding machines, the combination, with the driving-drum, the bobbin-support, and the intermediate roller upon which the bobbin rests, a catch, a brake-block, and

a spring, of an oscillating needle plate or box, the needles therein, through which the threads pass on their way to the bobbin, and a revolving wing or wiper shaft acting on the needle when the threads break to move the needle box or plate and release the catch, thereby allowing the spring to operate the brake-shoe and separate the intermediate roller from the driving-drum, so as to stop the bobbin. 35

2. The combination, with a bobbin-support, a friction-drum, and an intermediate roller, of the drag apparatus consisting of the two bars or wires *r* and *t*, the tension-wire *u*, the wire *v*, and the sliding brake-block *g*, substantially as and for the purpose set forth. 40

3. The combination, with the movable bracket *e*, which carries the bobbin *f*, of the weighted wire *e'*, bent at *e''* and *e'''*, and the sliding brake-block *g*, substantially as and for the purposes described, and as shown. 45

The foregoing specification of my improvements in machinery for winding yarn signed by me this 1st day of October, 1886. 50

BENJAMIN ALFRED DOBSON.
